CALCULATING MACHINE

Daniel Broido, Cockfosters, near Barnet, England

Application February 9, 1942, Serial No. 430,071
In Great Britain April 24, 1941

2 Claims. (Cl. 235—60)

This invention relates to calculating machines of the kind comprising set-up mechanism, value-entering means, result registering mechanism adapted to be actuated by said value-entering means, and printing mechanism for printing the indications on the numeral wheels of the result registering mechanism.

The main object of the invention is to provide a calculating machine of the kind described adapted for easy operation by operating a single control member used commonly for the calculating and printing operations.

It is also an object of the present invention to provide a hand-operated calculating machine of the kind referred to in which either the calculating mechanism or the printing mechanism can be selectively operated by suitable manipulation of the handle controlling the drive.

A further object of the invention is to provide an arrangement in which the drive is successively connected to means for setting the printing mechanism and bringing it into operation and thereafter restoring the elements of said printing mechanism.

A further object of the invention is to provide means whereby the result registering mechanism may be cleared, if desired, simultaneously with the restoration of the elements of the printing mechanism.

The foregoing objects are attained by a novel constructive arrangement in the mechanism embodying the invention, which will now be described with reference to the drawings, the novel features being set forth in the appended claims.

In the drawings,

Figures 1 and 1A together represent a perspective view of a machine made according to the present invention;

Figures 2 and 2A together represent a vertical section through the machine of Figure 1, taken on line II—II of Figure 3A;

Figures 3 and 3A together represent a horizontal section taken on line III—III of Figures 2 and 2A, omitting certain parts for the sake of simplicity;

Figure 4 is a partial front elevation of the machine, illustrating the stepping device for the carriage;

Figures 5 and 5A together represent a section through the driving shaft of the machine;

Figure 6 is a section on line VI—VI, Figure 5;

Figure 7 is a section on line VII—VII of Figure 5;

Figure 8 is a section on line VIII—VIII of Figure 5;

Figure 9 is a view taken in the direction of the arrow in Figure 8;

Figure 10 is a section on line X—X of Figure 5;

Figure 11 is a timing chart for the printing operation;

Figure 12 is a sectional view taken approximately on line XII—XII, Figure 3A, and on line XII—XII, Figure 13, illustrating the paper and ribbon feed; and,

Figure 13 is a section taken on line XIII—XIII of Figure 12.

General arrangement

As shown in Figures 1—3A, the machine is mounted on a base plate 1 between side frames 2, 4, suitably braced together by means of a tie-rod 5 and provided with a cover 6. The set-up mechanism, comprising pin barrels 7 of the well known Odhner type, having finger tips 14 is arranged in the front part of the machine, as shown in Figure 1. The result register 8 is arranged above the set-up mechanism on the right-hand side, and the revolution register 9 is arranged in line with the result register 8 on the left-hand side of the machine. The printing device, including an ink ribbon 10 and a paper web 11, are mounted at the rear top part of the machine.

Set-up mechanism

The pin barrels 7 are of the customary type, each comprising driving pins 12 (Figure 2) slideable in radial slots in the barrels, a setting cam 13 with a finger tip 14 for selectively setting the driving pins 12, a retaining plate 15 (Figure 3A) and a plunger 16 for securing the cam 13 in any set position. The barrels further comprise the customary carry devices such as rockers 17 and restoring cams 18.

The general arrangement and operation of Odhner barrels are well known, so that it is sufficient to state that in order to set up a factor, the finger tips 14 on appropriate barrels are aligned with one or other of the numerals marked adjacent the tips (Figure 1). This movement of the setting cams 13 causes a corresponding number of driving pins 12 to be projected into a working position. When the barrels are rotated, these projecting pins mesh with gears connected to numeral wheels of the result register, each driving pin shifting the appropriate register wheel one step. Each revolution of the barrels in either direction is counted on the revolution register, which thus shows the multiplier (in case of multiplication) or the quotient (in the case of division).

In conventional machines of this type, the set-up amount is varied by decimal multiples by shifting the result register (and the revolution register) transversely of the barrels, which remain in a fixed axial position, and are thus aligned with register wheels of the required denominations. Contrary to this conventional arrangement having stationary barrels, in the present machine the barrels are arranged to be shifted relatively to the stationary registers; this has the advantage that a stationary printing device can be associated with the registers.

As shown in Figure 3, the barrels 7 are rigidly fixed by means of a key 19 to a sleeve 20 rotatably and slidably mounted on a stationary shaft 21. The key-way 22 of the key 19 extends along the sleeve 20 to accommodate a key 23 of a gear 24 adapted to be driven by means hereafter described. The hub of the gear 24 is furnished with a groove 25 into which protrudes a lug 26 fixed to the frame plate 3 (see also Figure 10). Thus, when the gear 24 is rotated, it causes the sleeve 20 and the barrels 7 fixed thereto to rotate, but, if the sleeve 20 is shifted axially as will be presently described, the gear 24 is prevented by the lug 26 from sharing this axial movement.

A disc 27 secured to the sleeve 20 by a grub screw 28 carries a one-tooth pinion 29 for driving the revolution register 9. Adjacent the disc 27 is mounted a plate 30 having a key 31 sliding in a key-way 32 in the stationary shaft 21. The plate 30 further carries a pin 33 protruding into a circular groove 34 in the disc 27. Thus, when the plate 30 is shifted with the barrel carriage as described hereafter, the sleeve 20 is also shifted along the shaft 21, but the plate 30 does not participate in a rotation of the sleeve 20. Another plate 35 is mounted on the right-hand end of the sleeve 20, which is furnished with a circular groove 36 into which protrudes a pin 37 carried on the plate 35; a key 38 is fixed to the plate 35 so as to slide in a key-way 39 in the shaft 21. The plates 30, 35 form the side frames of the barrel carriage; they are connected by a tie-rod 40 (Figure 2) supported by a bracket 41, and they carry a cover 42 furnished with slots 43 for the finger tips 14. A number of lugs 44 (see also Figure 4) are fixed to the rod 40, the spacing between two adjacent lugs 44 being equal to a sideways step of the barrel carriage. A bracket 45 is fixed to the base plate 1 adjacent the front of the machine, and it has a plate 46 on which a locating pawl 47 is pivoted as at 48. A spring 49 normally tends to press the pawl 47 between two lugs 44 so as to locate the barrel carriage. A release key 50 is slidably mounted in the top of the bracket 45 in line with the pawl 47; when the key 50 is depressed against the pressure of its spring 51, the pawl 47 is disengaged from the lugs 44, and the barrel carriage is free to be shifted by hand along the shaft 21 by means of any projecting part, such, for example, as a tip 14.

A key 52 is provided for stepwise movement of the carriage to the right, and a similar key 52' for movement to the left. On being depressed against its spring 53, the key 52 first depresses, by means of an arm 54, the release key 50, thus disengaging the pawl 47. On further depression, the key 52 forces a lever 55 to swing inwards against the tension of a spring 56. The lever 55, which has an arm 57, is pivotally mounted as at 58 in a bracket 59, which, in turn, is pivoted as at 60 in the bracket 45. Depression of the key 52 swings the lever 55 and arm 57 downwards, 78

i. e. clockwise, around the pivot 58 (as viewed in Figure 2) so that the arm 57 takes up a position below the lugs 44. This movement is limited by a stop (not shown), whereupon further depression of the key 52 moves the lever 55, arm 57, and bracket 59 around the pivot 60, i. e. in a plane perpendicular to the plane of movement around the pivot 58. Since the arm 57 is disposed on the opposite side of the pivot 60 to that of the lever 55 (see Figure 4) the resulting movement of the arm 57 around pivot 60 is first substantially upwards and then substantially to the right. During this movement around the pivot 60 (clockwise as viewed in Figure 4) the arm 57 strikes against a lug 44 and moves the carriage one step to the right. When the key 52 is released, the spring 56 first swings the arm 57 around the pivot 58 out of engagement with the lug 44, and then around the pivot 60 to the starting position, whereupon the pressure on the key 50 is released, and the pawl 47 again locks the carriage in position. The left-hand stepping key 52' and the associated parts 53'-60' are similarly arranged to shift the barrel carriage to the left. The transverse position of the barrel carriage is indicated by a pointer 42' (Figure 1).

Means for zeroising the barrels 7 will now be described. A bail 61 (Figures 3A and 2) is rotatably mounted on the sleeve 20 adjacent the left-hand barrel 7. An extension of the bail 61 protrudes forwardly through a slot 61' (Figures 1 and 4) in the cover 42, this slot being of approximately the same length as the slots 43 for the finger-tips 14. A bar 62 is secured to the end of the bail 61, and a plate 63 is pivotally mounted on the bar 62. A torsion spring 64 normally tilts the plate 63 out of the way of the finger-tips 14. For zeroising, a finger bit 65 formed on the plate 63 is pushed upwards; this causes the plate 63 to tilt towards the machine (clockwise as seen in Figure 2), so as to pick up the finger-tips 14 and to restore them as the finger bit 65 continues to be moved around the sleeve 20. The plate 63 is then restored to the initial (lower) position, and the spring 64 again tilts it away from the barrels 7 to allow for free passage of the finger-tips 14.

As indicated in Figure 2, the spring-loaded plungers 16 for locating the setting cams 13 pass through corresponding holes in the sleeve 20. When a plunger 16 rides over the top of one of the coating teeth 66 in the cam 13, its inner end enters a counter-sunk hole 67 in the stationary shaft 21. As soon as the barrels 7 are turned out of the normal position, the plungers 16 are out of line with the holes 67, and consequently they cannot ride over the tops of the teeth 66; the setting cams 13 are thus locked.

Result register

As best shown in Figure 3A, the result register, designated generally by 8, is mounted on a shaft 68 journaled in bearings 69, 70 in the side frames 3, 4 respectively. It comprises a plurality (in the present embodiment, sixteen) of numeral wheels 71, one for each denomination of the machine capacity, the peripheries being marked with the numerals 0-9. Each numeral wheel 71 carries a ten-tooth gear 72 on one side, and a one-tooth pinion 73 on the other side. These parts are made separately and riveted together as shown in the case of the wheel on the extreme right; although these parts are made as described, in order to simplify the drawings all

the wheels other than that mentioned are shown as integral with the parts to which they are rigidly fixed. The gears 72 are rotatable on the shaft 68, and they mesh with idler gears 74 rotatable on a stationary shaft 75. The idler gears 74 are adapted to be driven by barrel pins 12 when the barrels 7 are rotated. The one-tooth pinions 73 are adapted to co-operate with known rockers 76 pivotally mounted as in known constructions on a stationary shaft 77 (Figure 2) and having a slotted connection with the shaft 75, the arrangement being such that the slot in the rocker 76 permits the latter to be moved into two positions, it being located in either position by a spring-loaded plunger (not shown). On completion of a turn of the associated numeral wheel 71, the one-tooth pinions 73 cause the associated rockers 76 to swing away from the numeral wheels 71, whereby the sloped tails of the rockers 76 are shifted into the path of rockers 17 in the associated barrels 7. Thus, the rockers 17 are caused to swing sideways and into engagement with idler gears 74 driving the next higher numeral wheels 71, and to shift them one step, whereupon the rockers 76 are restored by cams 18 on the barrels 7. In this manner, the carry is effected as customary in machines of this type. The numerals on wheels 71 are visible through apertures 78 in the cover 6.

For zeroising purposes, the one-tooth pinions 73 are formed with sideways bent lugs 79 (only one of which is shown in Figure 3A) adapted to co-operate with elevations on a comb-bar 80 slidable in a key-way in the shaft 68. A spring 81 resting on a pin 82 normally forces the comb 80 into a recess having a sloped edge in the bearing 70, so that the elevations on the comb are not aligned with lugs 79, and the numeral wheels 71 are free to rotate when driven by the barrel pins 12. However, when a crank 83 rigidly secured to the shaft 68 is rotated, the end of the comb 80 is forced along the inclined edge of the recess in the bearing 70, and out of it, whereupon the elevations on the comb are aligned with lugs 79 on the pinions 73 fixed to the numeral wheels 71. On further rotation of the shaft 68, the comb elevations pick up the lugs 79 and restore the numeral wheels 71 to the initial or zero position, whereupon the comb 80 again enters the recess in the bearing 70. This recess is so shaped that this zeroising operation can be effected in one direction only.

In addition to this manual method of zeroising, the register 8 can be cleared by turning a gear 84 secured to the shaft 68 by a key 85, as hereafter described.

The numeral wheels 71 are located by double detents 86 (Figures 2 and 2A) biased by pressure springs 87 mounted in a bar 88 secured to the frame structure of the machine.

Revolution register

The revolution register, designated generally 9 in Figures 3 and 7, is mounted on a shaft 89 journalled in bearings 90, 69 in the side frames 2, 3 respectively. It comprises, in the present embodiment, eight numeral wheels 91, each having a gear 92 on one side and a collar 93 on the other side. Here again the gears 92 and collars 93 are, in practice, riveted to the numeral wheels 91, the rivets being omitted from Figure 3 for the sake of simplicity; in the drawings all the parts are shown as single units except for the parts on the extreme left. The gears 92 mesh with idler gears 94, rotatable on

shaft 75, and adapted to be stepped by the aforementioned one-tooth pinion 29 whenever the sleeve 20 is turned through a full turn. Contrary to the result wheels 71, which are marked with numerals 0-9, the wheels 91 of the revolution register are each marked with two sets of numerals, namely with white numerals 0-9 for positive revolutions, and with red numerals 1-9 for negative revolutions. Accordingly, the gears 92 have nineteen teeth.

The revolution register 9 is zeroised in the same manner as the result register 8. The gears 92 are each furnished with a lug 95 (only one of which is shown in Figure 3) co-operating with an elevation on a comb 96, which is slidable in a key-way in the shaft 89 and is normally forced by a pressure spring 97 into a recess in the bearing 90, the other end of the spring 97 being supported by a pin 98 in the shaft 89. When the shaft 89 is rotated, the comb 96 is first shifted to align its elevations with the lugs 95, which are then picked up and restored to the initial positions, whereupon the spring 97 again moves the comb 96 into the recess of bearing 90. A crank 99 and a gear 100 are rigidly fixed to the shaft 89, which can be turned either by hand (by turning the crank 99) or by turning the gear 100 as hereafter described.

Printing mechanism

As shown in Figures 2, 2A and 3, a gear segment 101 is arranged in line with each gear 72 and 92 of the numeral wheels of the result register and the revolution register respectively. Each gear segment 101 is rigidly fixed to a bush 102 rotatably mounted on a shaft 103, an arm 104 being fixed to each bush 102 on the opposite side of the shaft 103. The arms 104 are axially closer together than the gear segments 101, so as to reduce the printing space required for printing the factors and the result, as will be explained hereafter. The shaft 103 is journalled at each end in a lever 105 rockably pivoted as at 106 in the side frames 2, 4 respectively. Each lever 105 is connected by a pin 107 to a link 108, the other end of each of which carries a pin 109 (Figure 5) protruding through a slot in the side frame 2 or 4 respectively. Rotatably mounted on the pin 109 is a roller 110 which runs in a groove of an internal cam 111. This cam 111 is rotatably mounted on a shaft 112 and can be driven by means hereafter described. The cam 111 is so shaped that, when rotated, it causes the levers 105 to rock around the pivots 106, thus reciprocating the shaft 103 and the gear segments 101 mounted thereon. Normally, the gear segments 101 are out of mesh with the respective gears 72 and 92 of the registers, the shaft 103 being in the position indicated by a dotted circle 103' in Figure 2A. However, when the cam 111 causes the levers 105 to swing anti-clockwise, the shaft 103 is shifted into the position shown in Figure 2A, and the gear segments 101 are brought into mesh with the gears 72, 92. The arms 104 on gear segments 101 are connected by means of pins 113 to links 114, the other ends of which are connected by means of pins 115 to printing sectors 116, 116' (Figure 13) for the result register and the revolution register respectively. The printing sectors 116 and 116' are pivotally mounted on a shaft 117 supported at each end by an arm 118 pivoted as at 119 in the side frames 2, 4. Each arm 118 carries, as at 120, a roller

121, which is forced by a spring 122 (secured as at 123 to the frames 2, 4) on to a cam 124 rigidly mounted on a shaft 125 journalled in bearings 126 in the side frames 2, 4. The cams 124 are shaped so as to reciprocate the arms 118 and the shaft 117, and the printing sectors, the shaft 117 being then moved into the position 117' (Figure 2A). The printing sectors 116, 116' are provided with type numerals 128, and it will be understood that the printing sectors 116 have ten type numerals 0-9, whereas the printing sectors 116' have nineteen type numerals each, in accordance with numerals on the wheels 72, 92 of the result register and the revolution register respectively. The types associated with negative indications of the revolution register 9 may be different to those associated with positive indications; for instance, they may be smaller, or inclined, or furnished with a distinctive sign. A platen 127 is arranged adjacent the printing sectors; thus, when the printing sectors are moved to the right, as viewed in Figure 2A, an imprint is taken by means of an ordinary typewriter ribbon 10 on to a web of paper 11. The arms 104 of the gear segments 101 are normally supported by a bar 128 secured to the frame structure of the machine.

The gear segments 101 can be restored to the normal position by a restoring bar 129 which is supported at each end by a ball 130 pivotally mounted on the shaft 103. The bar 129 carries a roller 131 adapted to cooperate with a swing lever 132 rockably mounted as at 133 in a bracket fixed to the base plate 1. The swing lever 132 is biased clockwise by springs 134 attached at one end to balls 130, and at the other end to the stationary bar 128, so that it normally butts against a stop 135 on a bar 136 (Figure 8). The left-hand end of the swing lever 132 carries a roller 137 adapted to co-operate with a restoring cam 138 to be described more fully hereafter. When the restoring cam 138 is rotated, it causes the swing lever 132 to rock the restoring bar 129, thereby restoring the gear segments 101, whereupon the bar 129 and the swing lever 132 are restored by the springs 134.

In order to ensure correct printing, an aligning bar 139 is provided to align all printing segments 116, 116' prior to the printing operation.

This aligning bar 139 is carried on two arms 140 (Figure 7) pivotally mounted on the aforementioned bar 136 secured to the side frames 2, 4. The arms 140 are interconnected by a cross-bar 141, to which is fixed a bracket 142 carrying a roller 143. This roller 143 is adapted to co-operate with a cam 144 rotatably mounted on the shaft 112, a spring 145 anchored as at 146 in the frame 3 maintaining the roller 143 in contact with the cam 144. The arrangement is such that when the cam 144 rotates, it forces the aligning bar 139 into engagement with teeth on gear segments 101, so as to adjust them all in one line. Suitable slots are provided in the frame plate 3 for the bars 129, 141.

Driving shaft

The machine is driven by turning the shaft 112 by means of a crank 147 secured thereto (Figure 5A). The crank 147 carries a handle 148 rockably pivoted as at 149 and normally forced into engagement with a stationary stop 150 by a pressure spring 151. In order to turn the handle, it is first necessary to depress it downwardly so as to disengage it from the stop 150. Just prior to the completion of the necessary number of

turns, this downward pressure may be relieved, whereupon the spring 151 urges the handle 148 again into engagement with the suitably shaped stop 150. The shaft 112 is rotatably and shiftably mounted in bearings 152 and 153 in the side frames 3 and 4 respectively. Fixed to the bearing 152 is a block 154, in which is mounted a pressure spring 155 and a ball 156 co-operating with two counter-sunk depressions 157 in the shaft 112. By pulling the crank 147 outwardly, or by pushing it inwardly, the shaft 112 can be shifted to either of the two positions determined by the depressions 157, the spring-loaded ball 156 locating the shaft in either position. Further movement of the shaft 112 in either direction is prevented by a stop collar 158 abutting against the block 154, or by a disc 159 abutting against the bearing 153, respectively. The disc 159 is rigidly fixed to the shaft 112 and is furnished with a cut-out 160 into which fits a stationary lug 161 secured to the side frame 4. The arrangement is such that the driving shaft 112 can only be shifted axially when it is in the initial angular position, in which the cut-out 160 in the disc 159 is aligned with the stationary lug 161. As soon as the shaft 112 begins to turn, the cut-out 160 is no more in line with the lug 161 and consequently, the shaft cannot be shifted axially.

By pulling the crank 147 outwardly, the shaft 112 is shifted axially into what may be termed the calculating position, i. e. the position shown in Figure 5. In this position, two keys 162 secured to the shaft 112 are shifted into engagement with two corresponding key-ways in a gear 163 meshing with the gear 24 already mentioned with reference to the barrel carriage. Thus, if the shaft 112 is turned when in the calculating position, it turns by means of keys 162, gear 163 and gear 24 the sleeve 28 carrying the barrels 1, thus effecting the required calculation in the manner usual in this type of calculating machine. Fixed to the gear 163 is a ratchet wheel 164 adapted to co-operate with a spring-loaded pawl 165 (Figure 10). This pawl 165 is pivoted on the stationary shaft 15, its end protruding into a cut-out in the ratchet wheel 164. A wire spring 166 engaging a pin 168 carried on the pawl 165 is frictionally mounted on the hub of the ratchet wheel 164. As soon as the ratchet wheel 164 is rotated in either direction, the pawl 165 is swung in the corresponding direction out of the cut-out in the ratchet wheel 164, so as to co-operate with the teeth on the circumference of the ratchet wheel 164. Thus, the pawl 165 permits of continuing rotation of the ratchet wheel 164 in the same direction, but it prevents it from rotating in the opposite direction, thus ensuring that once a revolution has been started in one direction it will be completed in the same direction without reversing. A stationary lug 167 fixed to the side frame 3 prevents the gear 163 from being shifted axially.

When the driving shaft 112 is in the calculating position, a ball 168 (Figure 5) enters a circular groove 169 in the shaft 112. This ball 168 co-operates with a plunger 170, the other end of which rests on a rocker 171 pivoted as at 172 in a bracket 173 secured to the side frame 3. A spring 174 anchored as at 175 presses the rocker 171 on to the plunger 170, and thus maintains the ball 168 in engagement with the groove 169. The rocker 171 is arranged to swing in a slot 176 in the frame 3 in line with the key-way 22 in the sleeve 28 of the barrel carriage. When the driving shaft 112 is in the calculating position, the

rocker 171 just clears the sleeve 20, so that this sleeve 20 is free to rotate when driven by the gear 163. However, if the driving shaft 112 is shifted out of the calculating position, the groove 169 forces the ball 168 and the plunger 170 to swing the rocker 171 into the key-way 22 in the sleeve 20, thus locking it in position.

When the crank 147 has been pushed inwardly, the shaft 112 will shift axially to the left into what may be termed the printing position. In this position, the shaft 112 is disengaged from the barrel carriage, and it is coupled to means for effecting the printing operation. These printing means will now be described.

As already mentioned, the shaft 112 carries two cams 111 for engaging the gear segments 101 with, and disengaging them from, the gears 72, 92 of the registers 8, 9 respectively. The right-hand cam 111 (as seen in Figure 5) is rotatably mounted on the shaft 112 and is provided with two key-ways 177 adapted to receive two keys 178 secured to the shaft 112. The left-hand cam 111 is formed with a hub 179 rotatable on the shaft 112 and journaled in a bearing 180 in the side frame 2. Rigidly mounted on the hub 179 is a sprocket wheel 181 adapted to drive, by means of a chain 182, another sprocket wheel 183 secured to the aforementioned cam shaft 125 (Figure 2A). The hub of the sprocket wheel 181 is extended to accommodate a sleeve 184 rotatably mounted on the shaft 112, and is fixed both to the hub 179 and to the sleeve 184, thus connecting them to form one integral unit. The other end of the sleeve 184 is slotted to receive the keys 162 when the shaft 112 has been shifted to the left, viz: into the printing position. Thus, when the shaft 112 is in the printing position, both cams 111 and all parts connected thereto are coupled to the shaft 112, and when this shaft is rotated, all these parts will also be rotated.

Rigidly fixed to the left-hand cam 111 is a ratchet wheel 185 adapted to co-operate with a spring-loaded pawl 186 pivoted as at 187 in the side frame 2 (see also Figure 6). The teeth in the ratchet wheel 185 are so shaped that it can be rotated in one direction only, i. e. anticlockwise as indicated in Figure 1.

The meshing cams 111 carry gear segments 188 adapted to mesh with the zeroising gears 84 and 100 of the result register 8 and the revolution register 9 respectively. The zeroising segments 188 are fixed to the cams 111 in such a position as to effect the zeroising operation after the cams 111 have brought the gear segments 101 into mesh with the gears 72, 92 of the registers. The sleeve 184 carries the aligning cam 144 adapted to operate the aligning bar 139 already described, and the restoring cam 138 which is now to be described in full detail.

The restoring cam 138 is a double cam comprising two circumferentially offset lobs or elevations 138 and 138'. It is slidable on the sleeve 184, but it is prevented from rotation independently from the sleeve by a stud 189 engaging a slot 189' in the sleeve 184. The double cam 138 is formed with a circumferential groove 190, with which co-operates a shift lever 191 pivotally mounted as at 192 on the shaft 136 and adapted to be rocked around its pivot 192 by a fork 193 (Figures 8, 9) pivoted as at 194 in a bracket 195 secured to the side frame 2. The other end of the fork 193 is connected by a link 196 to a rod 197 linked as at 198 to a lever 199 rockably mounted on the shaft 125. A hand lever 200 is pivoted as at 201 in the lever 199. This hand

lever 200 protrudes through a slot 202 in the machine cover 6, and is forced by a torsion spring 203 into one of two recesses formed in a side of the slot 202. These recesses determine two positions of the hand lever 200, which are marked "Non-clear" and "Clear" respectively.

The swing lever 132 co-operating with the restoring bar 129 is arranged between the two elevations of the cam 138. The swing lever 132 has two rollers 137 rotatably mounted on a pin 204 on each side of the swing lever 132. The arrangement is such that when the hand lever 200 is shifted to the "Non-clear" position, i. e. the position shown in Figure 5, the double cam 138 is then aligned with that one of the rollers 137 which is adapted to co-operate with the elevation 138, the other roller 137 being idle. When the hand lever 200 is shifted to "Clear," the cam 138 is shifted to the left, so that the other roller 137 will co-operate with the elevation 138' when the restoring cam is rotated, the first roller 137 remaining idle. As the elevations 138 and 138' are circumferentially off-set, the swing lever 132 will be operated sooner or later according to the axial position of the restoring cam as determined by the hand lever 200.

Paper feed

The platen 127 of rubber or other suitable material is mounted on a shaft 205 journaled in bearings 206, 207 in side frames 2, 4 respectively (Figure 13). The paper reel 11 is mounted on a wooden tube 208 (Figure 12) rotatable on a shaft 209 placed in U-shaped extensions of side frames 2, 4, a distance tube 209' on each side of the reel 11 serving for axial location. Rubber rollers 210, 211 (Figures 2A and 12) are arranged adjacent the platen 127 so as to provide a certain amount of friction sufficient to feed the paper strip when the platen is being turned. Guides 212 suitably shaped to facilitate the introduction of paper are suspended on shafts of rollers 210, 211. The platen 127 can be turned by hand by means of knobs 213 rigidly mounted on either end of the shaft 205.

The paper strip is stepped automatically after each printing operation as shown in Figures 12, 13. A ratchet wheel 214 is rigidly mounted on the shaft 205, and a bail 215 carrying a pawl 216 pivoted as at 217 is loosely mounted on the shaft 205 adjacent the ratchet 214. A torsion spring 218 presses the pawl 216 into engagement with the ratchet 214. Slidably mounted on a bolt 219 fixed to the bail 215 is a rod 220, the other end of which is linked as at 221 to a plate 222 secured to the right-hand arm 118 supporting the printing sectors 116. It will be seen that when the arms 118 swing clockwise as viewed in Figure 12 to take an imprint, the rod 220 causes the bail 215 to swing anti-clockwise, the pawl 216 thus skipping the teeth of the ratchet 214. The end of the rod 220 embracing the bolt 219 is slotted, so that when the arms 118 are restored and the rod 220 is shifted to the left, the bail 215 remains stationary for a lapse of time sufficient for the printing sectors 116, 116' to move a certain distance away from the platen 127, whereupon the bail 215 is swung clockwise and the pawl 216 shifts the ratchet 214 one step in the same direction, thus stepping the paper 11. A second pawl 223 pivoted as at 224 and biased by a torsion spring 225 prevents the ratchet 214 from turning backwards.

The paper strip can be cut off on a knife 226 secured to the side frames 2, 4.

Ink ribbon

As shown in Figures 12, 13, the ink ribbon 10 is coiled in the customary drums 227, 228 mounted on squared ends of vertical shafts 229, 230 journalled in brackets 231, 232 secured to the side frames 2, 4 respectively. Bevel gears 233, 234 are rigidly mounted on shafts 229, 230 respectively. A horizontal shaft 235 is rotatably and slidably journalled in the side frames 2, 4, its ends protruding through holes in the machine cover 6, so that it can be shifted into one or the other of two axial positions. The shaft 235 carries two bevel gears 236, 237; when it is shifted to the right, bevel 236 is out of mesh with bevel 233, and bevel 237 is in mesh with bevel 234. When the shaft 235 is shifted to the left, bevel 236 engages its associated bevel 233, and bevel 237 is shifted out of mesh with the bevel 234. Thus, when the shaft 235 is shifted to the right and turned clockwise as viewed in Figure 12, it will cause the right hand drum 228 to turn clockwise as viewed in Figure 13, thus shifting the ribbon 10 to the right; when the shaft 235 is shifted to the left, its clockwise rotation will cause the left-hand drum 227 to turn anti-clockwise, thus shifting the ribbon to the left. A gear 238 is rigidly mounted on the shaft 235; it meshes with a gear 239 journalled as at 240 in the side frame 4. The gear 239 meshes with a gear 241 secured to the shaft 205 of the platen 127. Thus, when the shaft 205 is turned after each printing operation as already described, the shaft 235 is also turned, thus shifting the ribbon 10 one way or the other, as required. A spring 242 secured as at 243 to the side frame 4 co-operates with grooves 244 to arrest the shaft 235 in either axial position.

The ribbon 10 is guided by pins 245 secured to brackets 231, 232. Further, it is supported by a guide 246 mounted on the tie-rod 5. The guide 246 is of flexible material and is arranged to move the ribbon 10 away from the platen 127 when the printing sectors 116, 116' are restored after the printing operation.

Printing operation

The sequence of the printing operation is best explained with reference to the timing chart, Figure 11. The various cams and other parts effecting the printing operation are so offset around the driving shaft 112 that they work in properly timed succession. The meshing cams 111 come into operation first, and shift the gear segments 101 into engagement with the gears 12, 92 of the registers. As soon as the gear segments 101 are properly in mesh, the gear segments 108 begin to turn the zeroising gears 84 and 100 of the registers, thereby rolling the amounts indicated by the result register 8 and the revolution register 9 on to the gear segments 101, which adjust the printing sectors 116 and 116' accordingly. When the zeroising operation is completed, the aligning cam 144 operates the aligning bar 139 in preparation for the printing. As soon as the aligning bar has properly aligned the sectors 116 and 116', the printing cams 124 release the supporting arms 118 which, under the influence of the springs 122, cause the printing sectors to press the ribbon 10 on to the paper 11 and to take an imprint, whereupon the cams 124 on further rotation restore the supporting arms 118. As soon as the printing sectors 116, 116' 75

are sufficiently removed from the platen 127, the restoring operation can begin. Assuming that the hand lever 200 has been previously set to the "Non-clear" position, the elevation 138 on the double restoring cam begins now to rock the swing lever 132, thus restoring the gear segments 101. As at this time the gear segments 101 are still in mesh with the gears 12 and 92 of the registers, these gears will turn the associated numeral wheels exactly the same amount as they have been previously moved during the zeroising operation, but in the opposite direction. Consequently, on completion of the restoring operation, always assuming that the hand lever 200 is on "Non-clear," the result register 8 and the revolution register 9 will show exactly the same indications as before the printing operation. Assuming now that prior to the printing operation the hand lever 200 has been set to the "Clear" position, this will have caused the double restoring cam 138 to slide axially so as to bring the second elevation 138' into co-operation with the restoring lever 132. This second elevation 138' is so positioned that it comes into operation after the cams 111 have disengaged the gear segments 101 from the registers, as shown in Figure 11. Consequently, when the second elevation 138' on the double cam 138 effects the restoring operation by causing the gear segments 101 to move into the initial position, this does not affect the numeral wheels of the result register 8 and the revolution register 9, which remain in zero position. In other words, if the hand lever 200 has been set to "Clear," the printing operation automatically clears the registers.

It will be seen from the foregoing description that when the driving shaft 112 has been shifted into the calculating position, the machine works in a manner similar to that of other machines 40 of repeated-addition type, the difference being that in order to increase or decrease the set-up amount by decimal multiples, the set-up mechanism comprising the barrels 7 is stepped sideways relatively to the stationary registers, whereas in conventional machines the registers are shifted relatively to the stationary set-up mechanism. Indications on the registers may be printed at will whenever desired, and it will be evident that every revolution of the driving shaft 112 when in printing position will print all indications of the registers, including zeros.

In the case of multiplication, the operation is as follows: The multiplicand is set up on the barrels 7, which are in the initial axial position. 55 One revolution of the driving shaft 112 in calculating position transfers the multiplicand to the result register 8. The driving shaft 112 is now shifted to the printing position and turned, the hand lever 200 being on "Non-clear." The multiplicand is thus printed on the right-hand side of the paper web 11, and the single calculating revolution of the driving shaft is registered on the left-hand side of the paper as "1." The driving shaft is now again restored to the calculating position, and the calculation is carried out in the usual way, the barrels 7 being shifted axially when required. When the calculation has been completed, i. e. when the required multiplier is indicated on the revolution register 9, the driving shaft 112 is again shifted to the printing position and turned, the hand lever 200 being on "Clear." Thus, the result and the multiplier are printed, and both the result register 8 and the revolution register 9 automatically zeroised. It will be noted that the whole calculation is re-

corded on two printed lines on the paper strip, thus

00000001	0000000000000015
	(multiplicand)
00000012	00000000000000180
(multiplier)	(product)

The machine according to the present invention is particularly suitable for calculations involving a constant multiplicand which has to be multiplied by different multipliers, as in this case the multiplicand can be printed once for a whole series of various multipliers, the registers (but not the barrels) being automatically cleared after each calculation.

In the case of division, the operation is similar; it is recorded in three printed lines, the first line comprising the divisor and "1," the second comprising the dividend and "2," and the third line comprising the remainder on the right-hand side and the quotient on the left-hand side thus:

00000001	0000000000000012
	(divisor)
00000002	00000000000000185
	(dividend)
00000015	00000000000000005
(quotient)	(remainder)

In order to effect a division the divisor is set up on the barrels, the handle is rotated once in a positive direction, and the first line is printed, as shown, the machine being set for "Non-clear." The result register is then cleared and the barrels reset for the dividend, the handle is again rotated once in a positive direction, and the second line is printed. The revolution register is now cleared, the barrels re-set for the divisor, and the handle is rotated negatively, with axial shift of the carriage if necessary, until a remainder smaller than the divisor appears on the result register. The machine is now set to "Clear" and the third line is printed.

Alternatively, if the full capacity of the machine is not utilised, the divisor and the dividend can be printed in the same line and in the same operation, one factor being printed on one side of the result register, and the other factor on the other side.

The fact that the machine prints all ciphers, both to the left and to the right of each printed figure, greatly facilitates the setting of the decimal point.

While the machine described in the foregoing specification is of the barrel type, it will be evident to those skilled in the art that this invention may be equally well applied to machines not using the barrel set-up. It will also be understood that the machine as described can be supplemented by commonly known features such as a bell, a direction indicator, and the like, a description of which has been omitted as it is not essential for the proper understanding of the present invention.

Instead of printing the indications of both registers it will be evident that the indications of one register only may be printed, for example by omitting printing elements and associated parts cooperating with the revolution register.

An advantage of the invention is that in a calculating machine fitted with only two registers all the factors and the result of a calculation can be printed.

5. What I claim is:

1. In a calculating machine comprising axially shiftable rotary set-up mechanism and, value-entering means axially fixed, result registering mechanism adapted to be actuated by said value-entering means, and axially fixed printing mechanism, a main driving shaft, bearings in which the main driving shaft is rotatably and shiftably mounted, an operating handle operatively connected to said main driving shaft by means of which said shaft may be rotated and shifted axially, an axially fixed gear wheel loosely mounted on said main driving shaft, an axially fixed gear wheel in permanent mesh with said loosely mounted gear wheel and adapted to be driven thereby to rotate said value-entering means in any axial position thereof, actuator means for operating said printing mechanism to effect the printing operation and means for limiting the extent of axial shift of said shaft in either direction to bring the shaft into one of two operating positions, in one of which the shaft is coupled to said loosely mounted gear wheel to drive said rotary value-entering means and in the other of which the shaft is coupled to said actuator means to operate said printing mechanism to effect the printing operation.
2. In a calculating machine comprising axially shiftable rotary set-up mechanism and value-entering means and calculating mechanism including axially fixed register wheels, and axially fixed printing mechanism comprising printing sectors, means for meshing said printing sectors with said register wheels, and means for zeroising said register wheels to adjust said sectors in accordance with the indications on the register wheels' actuator, means for operating said printing mechanism to effect the printing operation, and means for restoring the printing sectors, a main driving shaft, bearings in which the main driving shaft is rotatably and shiftably mounted, an operating handle operatively connected to said main driving shaft by means of which said shaft may be rotated and shifted axially, an axially fixed gear wheel loosely mounted on said main driving shaft, an axially fixed gear wheel in permanent mesh with said loosely mounted gear wheel and adapted to be driven thereby to rotate said value-entering means and means for limiting the extent of axial shift of said shaft in either direction to bring the shaft into one of two operating positions, in one of which the shaft is coupled to said loosely mounted gear wheel and rotary movement of the handle drives said calculating mechanism only, and in the other of which the shaft is coupled to said actuator means and rotary movement of the handle drives successively said means for meshing said printing sectors with said register wheels, said means for zeroising said register wheels, said means for effecting the printing operation, and said means for restoring the printing sectors.

DANIEL BRODIO.
